(57) **CLAIM**

The ornamental design for a wearable blanket, as shown and described.

DESCRIPTION

FIG. 1 is a front, top perspective view of a wearable blanket, showing my new design in a wearable configuration;

FIG. 2 is a rear, bottom perspective view thereof;

FIG. 3 is a bottom perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a front, top perspective view of the wearable blanket in a stored configuration; and,

FIG. 11 is a rear, bottom perspective view of the wearable blanket in a stored configuration.

The dashed broken lines in the figures are for the purposes of illustrating portions of the wearable blanket that form no part of the claimed design.

The short-short-long dashed broken lines immediately adjacent to the claim area in FIG. 3 and FIG. 9 are for the purposes of illustrating the boundaries of the wearable blanket, and form no part of the claimed design.

1 Claim, 11 Drawing Sheets
